TORPEDO DEFLECTOR

Alfred Alexander Jubie, Cloquet, Minn.

Application July 10, 1942, Serial No. 450,459

2 Claims. (Cl. 114—240)

The invention relates to means to prevent a torpedo from striking a boat and being exploded by impact against the hull of the boat, and more particularly to shock absorbing and deflecting means for mounting on the sides of the boat for cushioning the forward motion of the torpedo and deflecting the same in a direction rearwardly of the boat so as to cause the torpedo to harmlessly take a course away from and to the rear of the boat, the primary object of the invention being to provide an arrangement of this character which can be installed on a boat without substantial mechanical change in the structure of the boat.

Other important objects and advantages of the invention will be apparent from a reading of the following description taken in connection with the appended drawings, wherein for purposes of illustration a preferred embodiment of the invention is shown.

In the drawings:

Figure 1 is a fragmentary diagrammatic view in top plan showing the bow portion of a boat equipped in accordance with the present invention.

Figure 2 is a fragmentary side elevational view of Figure 1.

Figure 3 is an enlarged fragmentary transverse vertical sectional view taken through Figure 2.

Figure 4 is an enlarged top plan view of one of the deflector bars.

Referring in detail to the drawings, the numeral 5 generally designates the hull of a boat having the bow portion 6. Supported along the bow portion and along the opposite sides of the hull are deflector units 7 consisting of upper and lower continuous sprocket chains 8 and 9, respectively, which at regular intervals have links 10, illustrated in Figure 4 of the drawings having upper and lower vertical flanges 11 which are bolted as indicated by the numeral 12 to the flange 13 of angle irons 14 which include the laterally outwardly projecting flange 15, the space between the flanges and around the edges of the flanges being filled by a spherical segmental cushion 16 of rubber or other suitable material, the curved surface 7 thereof facing laterally and rearwardly.

Below the upper sprocket chain 8 and above the lower sprocket chain 9 the deflector bars 14 have upper and lower track brackets 18 and 19, respectively, which ride on the upper edges of the flanges of upper and lower tracks 20 and 21, respectively, which are suitably supported, as

shown, to bear the weight of the deflector bars 14.

At the opposite ends of the chains are sprocket wheels which are fixed on depending shafts 22 and 23, which are shown in Figure 3 as laterally displaced with respect to the side of the hull 5, the outer sprocket shafts 22 terminating adjacent the upper sprockets while the inner sprocket shafts 23 extend between the sprockets. The sprocket shafts are mounted in vertical portions 24 and 25 of upper and lower shock absorber brackets 26 and 27, respectively, which are horizontally and laterally inwardly and outwardly movable in hydraulic shock absorbing cylinders 29 and 30 which are mounted at vertically spaced points on the side of the hull 5, so that the deflectors are positioned sufficiently below the water line of the hull and rise sufficiently along the side of the hull above the water line to protect the hull. Mounted above the shock absorber cylinders and in conjunction therewith are the electric or other suitable motors 31 having their shafts 32 operatively connected by suitably housed and mounted gearing 33 with both of the sprocket shafts 22 and 23.

It will be observed that the forward ends of the deflector units are located relatively close to the side of the hull, while the rearward ends of the deflector units are relatively greatly spaced from the side of the hull so as to be outside of the forward end of the next deflector unit, whereby the deflector units diverge outwardly toward the stern of the boat, as clearly illustrated in Figure 1 of the drawings.

In the cases of the forwardmost deflector units 7a, these have tracks 20 and 21 angulated to conform with the contour of the bow portion of the boat as illustrated in Figure 1 of the drawings, the forward ends of the units 7a are driven from a twin power and shock absorbing unit similar in mechanical effect to the motors and shock absorbers 29 and 31, the unit 34 involving two motors together with their operating shafts 32a which are operatively connected to the sprockets at the forward ends of the units as illustrated in Figure 1 of the drawings.

In practice, it has been found expedient and practical to brace and thus suitably reinforce each unit, this by passing a running cable 35 around the same. Each cable is appropriately anchored and preferably located adjacent the vertical mid-portions of the angle irons 14 in the manner illustrated in the drawings. This arrangement appreciably strengthens the parts as needed.

It will be seen from the foregoing that with the outboard flights of the deflector units traveling rearwardly in the direction of the arrows, thereby presenting the deflector cushions 16 in a rearwardly and outward direction, the nose of a torpedo coming in contact with the rearwardly and laterally outwardly traveling deflector bars will be turned rearwardly and away from the side of the boat, with such gentle impact relative to the boat that the torpedo will remain unexploded and pass harmlessly to the rear or astern of the boat, and leave the boat uninjured. The deflector units are driven at suitable speeds in accordance with their construction and arrangement, to effectively deflect the torpedoes as described which would otherwise injuriously contact the sides of the hull of the boat.

Although there is shown and described herein a preferred embodiment of the invention, it is to be understood that it is not desired to limit the application of the invention thereto, except as may be required by the scope of the subjacent claims.

Having described the invention, what is claimed as new is:

1. A torpedo deflector for the hull of a boat comprising deflector units arranged alongside the hull in succeeding relation from the bow of said hull and each including upper and lower sprocket chains horizontally extending, upright deflector bars extending between said chains, front and rear pairs of upper and lower sprocket wheels, means to mount said pairs of sprocket wheels on said hull for yielding movement in pairs inwardly of said hull, guide means for said chains including tracks carried by said mounting means, and a motor drive for at least one pair of said sprocket wheels.

2. A torpedo deflector for the hull of a boat comprising a pair of upper and lower sprocket chains adapted to extend horizontally alongside said hull, upright deflector bars of angle iron form extending between said chains, transversely triangular cushions of resilient material fitting in said bars, front and rear pairs of upper and lower sprocket wheels around which said chains are trained, and means to mount said pairs of sprocket wheels on said hull with the rear pair spaced further from the hull than the front pair.

ALFRED ALAXANDER JUBIE.
